UNITED STATES PATENT OFFICE.

PAUL B. PARKS, OF OAK PARK, ILLINOIS, ASSIGNOR TO VAPOR CAR HEATING COMPANY, INC., OF CHICAGO, ILLINOIS, A CORPORATION OF NEW YORK.

VALVE-OPERATING MECHANISM FOR CAR-HEATING SYSTEMS.

Application filed January 29, 1927. Serial No. 164,490.

This invention relates to a valve operating mechanism for a car heating system, and more particularly to certain improvements in a car heating system which is automatically regulated to maintain the car atmosphere at one of two or more selected temperatures, for example, at a high temperature during periods of occupancy and at a lower temperature when the car is standing vacant in the train yard. A system of this type is disclosed in the patent to Russell, 1,440,701, granted January 2, 1923. Such a system includes an oscillatable control valve for governing the admission of steam or other heating fluid to the radiators, this valve being opened when the temperature falls below the desired point, and again closed when this temperature is once more attained. In the example shown in the patent referred to, the valve lever is moved in one direction or the other by a pair of opposed solenoids, the electric circuits for these solenoids being alternately energized in accordance with temperature changes.

The present invention relates to a novel and improved mechanism for operating this valve. A pair of heat-responsive elements (in the example shown, bellows diaphragms filled with an expansible fluid) are positioned one at each side of the valve operating lever, so that when one of these members is heated, it will expand and engage the lever and swing it to its other limit of travel. An electric heating element is associated with each diaphragm so that when a current flows through this element, the diaphragm will be heated and expand until the lever has been engaged and swung over to open or close the valve. A limit switch is also associated with the valve lever so that at the completion of either movement of the lever, the circuit to the heating element for the expanding member which has just operated, will be broken. The diaphragm will then gradually cool and contract to its original position. To accomplish the next movement of the valve lever, the other diaphragm will be heated by a circuit completed through the heating element for this second diaphragm, and the expansion of this diaphragm will result in swinging the lever to its first position. The completion of this movement of the lever will operate the limit switch to break the heating circuit for the second diaphragm.

The general object of this invention is to provide certain improvements in a car heating system, as briefly described hereinabove and as described in more detail hereinafter.

Another object is to provide an improved type of heat responsive motor for operating the valve lever of a car heating system.

Another object is to provide an improved automatic controlling means for a car heating system in which the control valve is moved by the expansion of motor elements due to the heating of these elements, by an electric current.

Another object is to provide an improved means for breaking the energizing heating current after the motor has been operated.

Other objects and advantages of this invention will be more apparent from the following detailed description of one approved form of the mechanism.

In the accompanying drawing, the invention is illustrated diagrammatically, some of the features being shown in elevation, some in section, and some are merely represented by well-known symbols.

Referring first to the main elements of the complete heat control system: A designates the steam train pipe of a railway car, B and C are two sections of a radiator, D is a valve for controlling the flow of steam to and from the radiators, E and F are motors for operating the valve, and G is the vapor regulator for controlling the pressure of the steam. At H is shown a limit switch which operates in conjunction with the relay J to bring about the alternate energization and de-energization of the motors E and F. K and L are respectively low and high temperature thermostats for determining the temperature to be maintained within the car, and M is a pneumatically operated selector switch which determines whether thermostat K or thermostat L shall be in control of the system. The switch or circuit breaker M is provided so that the apparatus may be made operative or inoperative, at will, and O is a pressure operated circuit breaker connected with the steam train line for breaking the electric operating circuit when there is no steam in said train line.

The particular features of novelty in this invention reside in the new form of operating motors E and F, and limit switch H, and the new combination of these features with the other mechanisms which have here-

tofore been in use. I will first briefly describe the entire system, so that the function and operation of these new features may be more clearly understood. The valve D comprises a casing divided by webs into a plurality of separate chambers 1, 2, 3, 4, 5 and 6, all communicating with a central circular valve chamber 7 in which is positioned a valve 8 provided with webs which in the different positions of the valve place certain chambers in communication with one another and cut off communication with other chambers. The valve 8 is swung to its different positions by the oscillating lever 9 positioned outside of the valve casing. When valve 8 is in the "open" position shown in the drawings, steam flows from the supply main A through the reducing valve of vapor regulator G and pipe 10 into the chamber 1, thence through valve chamber 7 and chamber 4 into the inlet pipe 11 of radiator B, then back through pipe 12 and into the inlet pipe 13 of radiator C and through return pipe 14 into the valve chamber 5. The steam and condensate flows from chamber 5 through chamber 6 and pipe 15 to the thermostat casing of the vapor regulator G, which is of well known construction and designed to regulate the supply of steam from the main A in accordance with the temperature of the steam returned from the radiators. When the valve is moved to the "off" or closed position, the steam entering through pipe 10 will pass directly from chamber 1 to chamber 6 and thence back through pipe 15 to the vapor regulator. The radiators and valve chambers 2, 3, 4 and 5 will be entirely cut off from the steam supply. The condensate returning to chamber 5 will pass through valve chamber 7 to chamber 2 and thence out through the drain pipe 16.

The valve operating lever 9 is moved from the "on" position shown in the drawings to the "off" position by means of the motor F, and is subsequently returned to the "on" position by means of the motor E. These two motors E and F are identical, except that they are opposed and positioned at opposite sides of one end of the valve lever 9. In the example here shown, each motor comprises a hollow diaphragm of bellows construction, comprising closed ends 17 and 18 and deeply corrugated side walls 19. The diaphragm is filled with a suitable fluid which expands quickly when heated. One end 17 of the bellows diaphragm is fixed to some suitable support, while the other end 18 is freely movable and carries a projection 20 adapted to engage a rounded enlargement 21 formed on valve lever 9. When cool, the motors will contract to the positions shown in solid lines in the drawing, but when heated the fluid will expand and the bellows will be extended to the position shown in dotted lines

in the case of motor E, the projection 20 engaging the lever 9 and moving it over to the other extreme of its swinging movement. In the example shown in the drawings, the motor E has last operated to move the valve to its "on" or open position, but the motor E has since that time cooled and returned to its original or normal position. The next operation will be caused by the expansion of the diaphragm of motor F, which will move the valve to "off" position. Each motor includes an electric heating element, here shown as a coil 22, which when traversed by an electric current will become heated and cause the expansion of the associated diaphragm. It should be understood that the motors E and F are shown diagrammatically in the drawings, and usually these motors would be positioned above the valve D, as shown in the drawings. For convenience of illustration, these motors have been positioned entirely to one side of the valve casing D, this showing requiring the undue lengthening of the valve lever 9, thus lengthening its arcuate movement and necessitating a longer expansion of the diaphragms of motors E and F. By positioning these motors closer to the pivotal center of lever 9, the necessary expansive movement would be greatly lessened.

The limit switch H comprises a pair of spaced contacts 23 and 24 which are fixedly mounted on some suitable support, and which are alternatively engaged by the contact 25 which is carried, by suitable installation 26, on an extension 27 of valve lever 9.

The relay J may be of any approved construction, and as here shown comprises a solenoid coil 28, which when energized draws up the core 29 carrying the contact plate 30. When in this position, the contact plate 30 makes connection between the pair of fixed contacts 31 and 32, and when the coil 28 is deenergized, the contact plate 30 falls and makes connection between the other pair of fixed contacts 33 and 34.

The thermostats K and L are here shown as of the mercurial type. The lead wire 35 always makes contact with the mercury columns 36 and 37 of the respective thermostats K and L. At a certain relatively low temperature, for example, 50° Fahrenheit, the mercury column 36 of thermostat K will make contact with a fixed contact member 38, to which is connected the lead wire 39. At a relatively higher temperature, for example, 70° Fahrenheit, the mercury column 37 of thermostat L will make contact with the fixed contact member 40 to which is connected the lead wire 41.

The selector switch M comprises a cylinder 42, closed at one end 43, and communicating with a pipe 44 leading from the air signal line of the car. Within the cylinder is a

piston 45, having a stem 46 on which is mounted the switch member 47. The switch member comprises a contact ring 48 mounted in an annular body of insulation 49. When 5 super-atmospheric pressure exists in the air signal line and pipe 44, the piston 45 will be forced out against the stops 50, at which time a ring of insulation 49 separates the spring contacts 51 and 52. When pressure 10 is released from the pipe 44 of cylinder 43, the spring 53 will force the switch member 47 and piston 45 inwardly until the member 47 engages the stop 54, at which time the contact ring 48 will be positioned between 15 and will electrically connect the spring contacts 51 and 52. Under emergency conditions, as hereinafter explained, the stem 55 may be pulled out to withdraw stop 54 against the action of spring 56, thereby permitting 20 the switch member 47 to be pushed in further by means of spring 53 so that a second ring of insulation 49 will again separate the spring contacts 51 and 52. When air pressure is again returned to the pipe 54 25 and cylinder 43, piston 45 will again be forced out against stops 50, and stop member 54 will again snap back into its original position to limit the inward movement of the switch member 47.

30 The switch N is an ordinary double knife switch, by means of which the entire control system is rendered operative or inoperative, as desired.

The circuit breaker O consists of a casing 35 57 at the end of a pipe 58 which communicates with the steam train line pipe A, the outer end of the casing being closed by a flexible diaphragm 59 provided with a stem 60 carrying a contact plate 61. When steam 40 pressure is present in the supply pipe A and hence in pipe 58 and casing 57, the diaphragm 59 will be pushed out to hold contact plate 61 against a pair of fixed contacts 62 and 63. When steam pressure is absent, 45 contact plate 61 will be withdrawn to break the circuit at this point.

The general operation of this system is as follows: We will first assume the conditions shown in the drawing, when the car is standing in a railway yard with its train pipe connected to a source of supply of steam, so that steam pressure is present in the steam supply pipe A, and in the circuit breaker O. However, the super-atmospheric air pressure 55 is absent from the pipe 44 and piston 43, since the air signal line is broken. It is now desirable to keep the car heated, but only to a comparatively low temperature, (for example, 50 degrees Fahrenheit), and the low 60 temperature thermostat K is in control of the system. As here shown, the temperature has fallen slightly below the desired temperature, and the valve D is opened so that steam is passing from the supply pipe A to the radiators B and C. Current flows from

the battery P through wire 64, contact plate 61, wire 65, blade 66 of switch N, wire 67, binding post 68, resistance 69, binding post 70, wire 71, coil 28 of relay J, wire 72, binding post 73, wire 74, blade 75 of switch N, 70 wire 76, back to the battery. This will be called Circuit No. 1.

Since solenoid J is now energized, the contact plate 30 will be held up in engagement with the fixed contacts 31 and 32. Steam 75 is now being supplied to the radiators and the temperature of the car will gradually rise until the mercury column 36 of thermostat K engages the fixed contact 38. At this time another circuit will be completed, as 80 follows:

Circuit No. 2.—Circuit No. 1 as far as binding post 70, wire 77, wire 35, mercury column 36, contact 38, wire 39, spring contact 51, contact ring 48, spring contact 52, 85 wire 78, binding post 79, wire 80, binding post 81, and wire 82 to binding post 73, and thence over Circuit No. 1 back to the battery. It will be seen that this circuit forms a shunt between binding posts 70 and 73 across the 90 coil 28 of relay J, so that the relay will be deenergized and the contact plate 30 will fall so as to connect the other pair of fixed contacts 33 and 34. This will complete one of the valve operating circuits as follows: 95

Circuit No. 3.—Circuit No. 1 to binding post 68, wire 83 to the movable contact plate 25 of limit switch H, fixed contact 23, wire 84, heating coil 22 of motor F, wire 85, contact 33, contact plate 30, contact 34, wire 100 86 to binding post 81, and thence over Circuit No. 2 back to the battery.

The heat given out by coil 22 will now expand the fluid in the diaphragm of motor F so that this diaphragm will expand 105 and push the valve operating lever 9 over to its opposite position so as to close the valve D. This swinging movement of valve lever 9 will cause the opposite end of the lever to swing in the other direction, moving the contact 25 of limit switch H from the fixed contact 23 to the fixed contact 24 and thus breaking Circuit No. 3 at this point. Current no longer passes through heating coil 22, and the diaphragm of motor F will 110 cool off and return to its original position. All parts will remain in the positions just described until the temperature of the car has fallen to such an extent that the mercury column 36 of thermostat K will move 115 down out of engagement with the fixed contact 38, thus breaking Circuit No. 2 at this point. Circuit No. 1 will now be again effective to energize the relay J and move the contact plate 30 up into engagement with the fixed contacts 31 and 32. The other valve operating circuit will now be completed, as follows:

Circuit No. 4.—Circuit No. 3 as far as movable contact 25 of limit switch H, con- 130

tact plate 24, wire 87, heating coil 22 of motor E, wire 88, contact 31, contact plate 30, contact 32, wire 86, and thence over Circuit No. 3 back to the battery P. The expandible diaphragm of motor E will now be heated and will move the valve lever 9 back to the position shown in the drawings with valve D open. The completion of this movement will shift the movable contact 25 of limit switch H off from the fixed contact 24 and break Circuit No. 4 at this point. The parts are now in the positions illustrated in the drawing, and the operations hereinabove described will be repeated at intervals so as to maintain the car temperature approximately at 50° Fahrenheit, or the temperature for which thermostat K is adjusted.

When the car is connected in service as a unit of a train, the presence of super-atmospheric air pressure in the pipe 44 and cylinder 43 will move out the switch member 47 so that the ring of insulation 49 is positioned between the spring contacts 51 and 52 of selector M. This will break the circuit through thermostat K and render same inoperative, so that when the car temperature rises to 50° Fahrenheit and mercury column 36 engages fixed contact 38, neither of the circuits 2 or 3 will be completed and the valve D will remain open. This condition will continue until a higher temperature, for example 70° Fahrenheit is reached, at which time the mercury column 37 of high temperature thermostat L will engage the fixed contact 40, thus completing another circuit as follows:

Circuit No. 5.—Circuit No. 2 through wire 35, mercury column 37, fixed contact 40, wire 41 to binding post 79, and thence over Circuit No. 2 back to the battery. This will operate the same as Circuit No. 2 to deenergize the relay J, and thus complete Circuit No. 3 and close the valve D. The succeeding operations will be the same as already described, with the exception that Circuit No. 5 is effective instead of Circuit No. 2. The car temperature will be maintained at approximately 70° Fahrenheit, or the temperature for which high temperature thermostat L is adjusted.

It will be noted that the resistance 69 is always present in circuits 1, 2 and 5 so as to cut down the current flowing through thermostats K and L, and relay J, but this resistance is not present in the motor circuits 3 and 4 so that a stronger current is permitted to flow through the heating coils 22. However, as soon as one of the motor movements is completed these strong motor currents will immediately be broken by the limit switch H. The only currents which are normally flowing are the relatively light currents through either one of the thermostats or through the relay J.

It will be noted that while the high tem-

perature thermostat L is in control when the car is in service, the low temperature thermostat K will be automatically made effective when the car is disconnected from a train, since the breaking of the air signal line will cause the switch member 47 of selector M to move into the position shown in the drawing again establishing the circuit through low temperature thermostat K. Whenever the steam supply is interrupted, the circuit breaker O will automatically break the electric control circuits by moving the contact plate 61 away from the fixed contacts 62 and 63. Also, the control circuits can be manually interrupted at any time by opening the master switch N.

Although for convenience in illustration a battery P has here been indicated as the source of electric energy, any other suitable source of power might be used, and it will be evident that this control mechanism will be equally effective if alternating current is used instead of direct current. In such case, however, a type of relay better adapted for use with alternating current would be substituted for the relay J here shown. Such alternating current relays are well known in the art. This is one of the advantages of this system over similar systems heretofore in use where solenoids were used as the operating motors E and F.

As already noted, the arrangement shown in the drawing is merely diagrammatic, and the operating lever 9 will normally be shorter, and the grouping of the valve D, motors E and F, and limit switch H will be much more compact than in the form illustrated in the drawings. The heating elements 22 are merely illustrated diagrammatically and may be associated with the expandible diaphragms in any manner which will provide the most efficient heating effect.

If for any reason it is desired to heat the car to the higher temperature while the car is in the yards, this may be done by withdrawing the stop 54, as already explained, which will place the high temperature thermostat L in control of the system. The return of air pressure to the cylinder 43, when the car is again in service, will push out the piston 45 and valve member 47, so that stop 54 will automatically return to its operative position as shown in the drawings.

I claim:

1. In a car heating system, the combination with a valve-operating arm, and a control system therefor comprising two alternatively energized electric circuits, of a pair of opposed motors for moving the arm and each motor being adapted to move the arm in one direction only, a motor being positioned at each side of the arm, each motor comprising a member which is moved into or out of contact with the arm in response to temperature changes, and an electric heat-

er for the member, the heater being included in one of the circuits.

2. In a car heating system, the combination with a valve-operating arm, and a control system therefor comprising two alternatively energized electric circuits, of a pair of opposed motors for moving the arm, a motor being positioned at each side of the arm, each motor comprising a member which 10 expands when heated to move the arm to a position where it remains when the member contracts, and a resistance member in one of the circuits for heating the member.

3. In a car heating system, the combination with a valve-operating arm, and a control system therefor comprising two alternatively energized electric circuits, of a pair of opposed motors for moving the arm, a motor being positioned at each side of the 20 arm, each motor comprising a diaphragm which expands when heated to move the arm to a position where it remains when the diaphragm contracts, and an electric heating element associated with the diaphragm and 25 included in one of the electric circuits.

4. In a car heating system, the combination with a valve-operating arm, and a control system therefor comprising an intermittently energized electric circuit, and a motor 30 for moving the arm comprising a hollow bellows diaphragm filled with an expansible fluid and having one end fixed and the other movable when the diaphragm is heated to push the arm to a position where it remains 35 when the diaphragm contracts, and an electric heating element associated with the dia-

phragm, and included in one of the electric circuits.

5. In a car heating system, the combination with a valve-operating arm and a control system therefor comprising two alternatively energized electric circuits, of a pair of opposed motors for moving the arm, each motor comprising a heating element included in one of the circuits, and a normally contracted expansible diaphragm, the diaphragm expanding when heated so as to engage and move the arm, and automatically contracting again when permitted to cool, thus moving out of engagement with the 40 arm, and a limit-switch for breaking the heating circuit for each motor as soon as its expanding movement has been completed.

6. In a car heating system, the combination with a valve-operating arm and a control system therefor comprising two alternatively energized electric circuits, of a pair of opposed motors for moving the arm, each motor comprising a heating element included in one of the circuits, and a normally contracted expansible diaphragm, the diaphragm expanding when heated so as to engage and move the arm, and automatically contracting again when permitted to cool, thus moving out of engagement with the 45 arm, and a limit-switch for breaking the heating circuit for each motor as soon as its expanding movement has been completed. 50
